UNITED STATES PATENT OFFICE.

JAMES H. WYATT, OF KIRKLYN, PENNSYLVANIA, ASSIGNOR TO WILLIAM M. SCOTT,
OF TREDYFFRIN TOWNSHIP, PENNSYLVANIA.

SWITCHING APPARATUS.

Application filed February 17, 1923. Serial No. 619,577.

To all whom it may concern:

Be it known that I, JAMES H. WYATT, a citizen of the United States, residing in Kirklyn, Delaware County, State of Pennsylvania, have invented certain new and useful Improvements in Switching Apparatus, of which the following is a specification.

My invention relates to switching or automatic circuit breaker mechanism utilizable for controlling or interrupting circuits carrying current for electric lighting, power or other purposes.

My invention resides in single pole or multi-polar switching or circuit breaker mechanism of the "non-closable" type, characterized by the utilization of an over-travelling toggle for locking the switching or circuit breaker mechanism in normal, generally circuit closing, position, in combination with a latch for detachably connecting an operating member with the toggle structure, the latch being actuated to rob the operator of control upon attempted closing of the switch or circuit breaker mechanism during existence of an abnormal or undesired condition; and further characterized, in the case of multi-polar switching or circuit breaker mechanism, by the utilization of a single latch co-operating with the toggles of the different poles.

My invention resides further in a multi-polar switching or circuit breaker mechanism of the non-closable type, and more particularly of the character above referred to, in which the armatures or movable systems of a plurality of tripping magnets control a tripper bar or member common to the poles and utilized in actuating the latch which normally connects the operating member with the switching mechanism; and my invention resides in structure of this character in which the magnets serve to trip or release the movable contact members of the poles with which they are associated and of any other pole or poles whose movable contact member or members is or are coupled to move in unison with said movable contact members.

My invention resides in switching or circuit breaker mechanism of the character above referred to when enclosed in a housing and operable and controllable from the exterior of the housing.

My invention resides in the features of structure and combination hereinafter described and claimed.

For an illustration of one of the forms my invention may take, reference is to be had to the accompanying drawings, in which:

Fig. 1 is a side elevational view of apparatus embodying my invention, a side wall of the housing being partially cut away.

Fig. 2 is a front elevational view of the structure shown in Fig. 1, a portion of the front wall of the housing being cut away.

Fig. 3 is a side elevational view, partly in section, on enlarged scale, of part of the mechanism in circuit closing position.

Fig. 4 is a bottom plan view of part of the structure shown in Fig. 3.

Fig. 5 is a side elevational view of part of the structure of Fig. 3 with the parts in open circuit position.

Figs. 6 and 7 are side and end elevational views, respectively, of the latch.

Figs. 8 and 9 are, respectively, side and plan views of the latch actuator.

Figs. 10 and 11 are, respectively, side and plan views of the operating member.

Fig. 12 is a fragmentary side elevational view, partly in section, of parts of the tripping mechanism.

Figs. 13 and 14 are, respectively, plan and side views of a toggle link.

Fig. 15 is a fragmentary side elevational view of a group of elements.

Fig. 16 is a fragmentary front elevational view of another group of elements.

Referring to the drawings, 1 is a base of suitable insulating material on which are mounted, as indicated in Fig. 2, three poles, A, B and C, of a multi-polar automatic circuit breaker mechanism, whose movable contact members are mechanically connected to cause movement of them in unison with each other, it being understood, however, that some features of my invention are utilizable in connection with single pole switching or circuit breaker mechanism.

Each of the poles comprises main terminals 2 and 3, adapted to be engaged and bridged by the movable laminated contact member 4 secured upon the arm 5 pivoted at 6 to a bracket or housing 7 secured to and outstanding from the base 1. Pivoted to

- the arm 5 at 8 is a toggle link 9, pivoted at 10 to the toggle link 11 pivoted at 12 to the bracket or housing 7, and having a portion 13 extending outwardly beyond the pivot 12, 5 Figs. 13 and 14. The members 11 of the several poles are mechanically coupled by the bar 14, preferably of insulating material, causing the toggles and movable contact members to move in unison with each other 10 or as an unit.

The base 1 and the mechanism carried thereby are supported and carried by the rear box or housing 15, which may be of sheet metal, and which is itself secured to 15 any suitable support by screws 16, the box 15 being a support for the base 1 and the parts carried thereby and for the housing H, which encloses the switching mechanism and carries operating or control mechanism 20 therefor.

Communicating with the interior of the box 15 is the pipe or conduit 17, through 25 which extend from the exterior into the box 15 the three insulated supply conductors 18, 19 and 20, connecting within the housing 15 with the studs 21, which extend through the base 1 and connect with the upper terminals 2 of the several poles, as A, B and C.

With each of the lower terminals 3 of the 30 outside poles or arms A and C is connected one terminal of an overload tripping coil 22 whose other terminal connects with a stud 23 extending through the base 1 into the box 15 and there connecting with the consumption 35 circuit conductors 24 and 25 which, with the consumption circuit conductor 26, connected to a stud 23 connecting with the lower terminal 3 of the middle arm or breaker B, extend to the exterior of the box 40 15 through the pipe or conduit 27.

Associated with each tripping coil 22 is 45 a core structure with which co-operates the armature 28, pivoted at 29, and provided, when desired, with a start-delaying device of the sucker type comprising a cup 30 within which is the movable sucker element 31 connected by link 32 to the armature 28.

The toggle links 9, 11 form, for each pole, 50 a toggle which overtravels, in the sense that the center of the pivot 10 moves upwardly beyond or across a line connecting the centers of pivots 8 and 12, until the extension 13 of the toggle link 11 comes into contact with bracket or housing 7, thereby forming a lock which holds the movable contact members 4 under tension in circuit closing position, all as indicated in Fig. 1.

Associated with each overload tripping 60 magnet is a member 33, Figs. 1, 2 and 12, which upon attraction of the armature 28, upon overload, is struck at its lower end by the armature 28, causing member 33 to move upwardly and engage the tail 13^b of the toggle link 11, causing its rotation in counter-clockwise direction, as viewed in Figs. 1,

3 and 12, causing the pivot pin 10 to move in counter-clockwise direction across the line joining the centers of pivots 8 and 12, so causing the toggle to become undertravelled and collapse and thereby cause or allow the 70 movable contact member 4 by gravity or a spring (not shown) to rotate in clockwise direction about its pivot 6 to open circuit position.

Each of the members 33 is provided with 75 a pin 34, Figs. 1, 2 and 12, upon which is loosely hung or pivoted the tripping bar 35, preferably of insulating material, extending across in front of the three poles, as indicated in Fig. 2.

Pivoted at 12 to the bracket or housing 7 associated with the middle pole or breaker B is the operating member or lever 36, Figs. 10 and 11, which may be formed in two parts joined by the saddle or member 37, 85 with which co-acts the actuator hereinafter described.

Pivoted upon the operating member or lever 36 at 38 is the latch 39 having the tails 40 and 41 and the lug 42, in the path 90 of which latter is a pin 43, carried by the member 36, limiting counter-clockwise rotation of the latch 39, as viewed in Figs. 1, 3 and 5. Surrounding the pivotal hub 39^a of the latch 39 is wound a spring 44 acting upon the latch 39 to tend to rotate the same in counter-clockwise direction, as viewed in Figs. 1, 3 and 5, one end of the spring 44 engaging the tail 40 and the other resting 100 against the pin 43.

Secured to the bar 14 and therefore to the toggle members 11 is the member or abutment 45, whose end is adapted to be engaged by the hook latch 39, as indicated in Figs. 1 and 3.

Pivoted at 46 to the bracket or housing 7 of the middle pole or arm B is the latch actuator 47, disposed beneath the tail 41 of the latch 39 and adapted to be moved in counter-clockwise direction by upward 110 movement of the tripper bar 35, which is disconnected from but supports latch actuator 47 and lies in the notch 47^a. Upon upward movement of the tripper bar 35 the latch actuator 47 engages the tail 41 of the latch 39 to move the same in opposition to spring 44 in clockwise direction about its pivot 38, as viewed in Figs. 1, 3 and 5, to disengage the latch 39 from the abutment 45, which latter is in effect fixedly connected to all of the toggle members 11 of the different poles.

Disposed upon the base 1 beneath the middle pole B is an underload or low or no-voltage magnet having the windings 48, associated with core structure having the poles 49, with which co-acts the armature 50 secured to the lever 51 pivoted to the bracket or housing 7 at 46. A tension spring 52, Fig. 1, is connected at its one end to the end 120

of the lever 51 beyond the pivot 46, and its other end at 53 to a stationary abutment, the tension of the spring 52 being exerted in such direction as to move the armature 50 away from the poles 49. When the magnet windings 48 are energized, the armature 52 is held in attracted position indicated in Fig. 1, in opposition to the tension of spring 50. Upon occurrence of low voltage or no voltage the spring 52 moves the lever 51 in counter-clockwise direction, as viewed in Fig. 1, and the pin 54 carried by the lever 51 engages the tail of the cam 55, Fig. 1, rotating the same in counter-clockwise direction about its pivot 46 and causing its free end at the right to engage the roller 38^a on outer end of pin 38, or, in any event, the operating lever 36, causing the latter to rotate in counter-clockwise direction upon its pivot 12, as viewed in Fig. 1, thereby lifting the latch 39 from the abutment 45, and the member 36 also engages the under side of the flanges 13^a of the toggle member 11 of the middle pole or arm B, rotating it in counter-clockwise direction, as viewed in Fig. 1, thereby carrying the toggles of all the poles backward across dead center to undertravelled position, whereupon they collapse and all the contact members 4 move to open circuit position.

The front wall of the housing H may be fixed with respect to the housing, as indicated, or it may be a pivoted door of the housing. In either event, as indicated, there is secured upon the housing wall upon the interior thereof the bracket 56, in which is pivoted the rotatable shaft 57, upon which within the housing H is secured the actuator 58 having the upper and lower lugs or hooks 59 and 60; the former, upon counter-clockwise rotation of the actuator 58, as viewed in Fig. 2, engages the portion 37 of the operating member or lever 36 to move the same in clockwise direction about its pivot 12, as viewed in Figs. 1, 3 and 5. And upon movement of the actuator 58 in opposite direction the lower lug or hook 60 engages the under side of the member 36, rotating it in counter-clockwise direction, so freeing the latch 39 from the abutment 45, if the switching mechanism is in circuit closing position, Figs. 1, 2 and 3, and thereafter rotating all the toggle members 11 in counter-clockwise direction to bring the toggles to undertravelled position, whereupon the movable contact members move to open circuit position.

Secured upon the shaft 57 on the exterior of the housing H is the operating handle 61 for imparting to the actuator 58 the rotative movements in opposite directions above described.

Secured to the housing H is a lug 62 having a hole 63 through which may extend the hasp 64 of a padlock 65, the hasp 64 passing

through an open notch or groove in the lug 66 on the operating handle member 61, whereby, until the padlock 65 is unlocked and hasp 64 removed, the actuator 58 cannot be effectively moved.

As indicated in Fig. 1, there is attached to and movable with the bar 14 a forwardly extending arm 67, which carries on its forward end an indicating or signaling element 68, which partakes of pivotal movement about the pivot 12, moving to different positions according as the circuit breaker mechanism is opened or closed. There is provided in the front wall of the housing H an opening, or an opening covered by glass or other transparent material, through which the indicating member 68 is visible, the position of the member 68, or its presence or absence from a position before the opening, indicating to the operator the position of the circuit breaker mechanism within the housing.

Outstanding from the base 1, within the housing H, and disposed between the upper portions of the poles or arms A, B or C, are the barriers 69, of insulating material, to prevent arcing across between poles or at the union of arcs at different poles at the moment the circuit is ruptured.

The operation is as follows:

With the circuit breaker structure in circuit closing position as indicated in Figs. 1 and 3, upon overload in either of the branches of the circuit including the poles A or C, the armature 28 of the corresponding magnet is attracted, moving upwardly the associated member 33 which carries upwardly with it also one end of the tripper bar 35, which in such upward movement, at its one end moves about the pivot pin 34 at its opposite end. This upward movement of the bar 35 causes counter-clockwise movement of the latch actuator 47, as viewed in Figs. 1 and 3, the latch actuator in turn engaging and moving the tail 41 of the latch 39, moving the latch in opposition to spring 44 to disengage from the abutment 45, which is in fixed relation to all the toggle members. Soon after the disengagement of the latch 39 from the member 45 the tail 40 of the latch 39 engages the tail 13^b of the toggle link 11, causing said toggle link to move in counter-clockwise direction, as viewed in Fig. 1. At the same time the upper end of the member 33, in the outside pole, moving upwardly by the action of the overload armature, engages the tail 13^b of toggle link 11 of the associated pole. Thus, two of the toggle members are given motion in counter-clockwise direction, the remaining pole or poles partaking of the same movement, the toggles being actuated from overtravelled to undertravelled position, whereupon they all collapse and the contact members 4 move to open circuit position, either under the in-

125

fluence of resilience of the contact members 4 alone, or assisted by gravity or a spring, not shown.

If the armatures 28 of both poles A and C should be simultaneously attracted, the same mode of operating prevails in that the bar 35 first causes disengagement of latch 39 from member 45, and thereafter the members 33 of both poles A and C actuate the toggles to carry them from overtravelled to undertravelled position.

With the parts in open circuit position, as indicated in Fig. 5, the circuit breaker may again be closed by first rotating the handle 61 in clockwise direction, as viewed in Fig. 2, causing the lower lug 60 of the actuator 58 to engage the under side of the operating lever 36, rotating the same in counter-clockwise direction as viewed in Fig. 5, until the latch 39 engages the abutment 45. Thereafter, the handle 61 is rotated in opposite direction, whereupon the upper lug 59 of the actuator 58 engages upon the top of member 37 of the operating lever 36, moving such lever in clockwise direction, as viewed in Fig. 5, the hook 59 then causing the bar 14 and the several toggle members 11 to rotate in clockwise direction, expanding the toggles and carrying the contact members 4 toward circuit closing position, which they reach when the toggles are fully extended, and slight further movement causes their overtravel to lock the contact members 4 in circuit closing position. Upon release of the operating handle 61 by the operator, a spring, not shown, returns the actuator 58 to neutral or mid position indicated in Fig. 2.

If during the circuit closing movement just described an overload condition exists in either or both poles A and C, either or both armatures 28 is or are attracted, causing upward movement of the tripping bar 35, which then causes actuation of the latch 39 through the medium of the latch actuator 47, the latch 39 being thereby disengaged from the abutment 45, thereby disconnecting the operating lever 36 from the toggle mechanisms, leaving them free to collapse and return the contact members 4 to open circuit position, and so effecting the "non-closable" function.

In event that the voltage upon the circuit becomes low or vanishes, the attraction of the poles 49 of the low voltage magnet upon the armature 50 diminishes to such extent that the spring 52 gains control of the lever 51, rotating it in counter-clockwise direction about its pivot 46, as viewed in Fig. 1, whereupon the pin 54 will engage the cam member 55, rotating it in clockwise direction, causing it to thrust upwardly upon the operating lever 36, which then rotates in a counter-clockwise direction, and the upper edge or face of the lever 36 engages a

flange 13^a of the toggle member 11 of the middle pole B, or engages the bar 14 or any other member in fixed relation thereto, causing all the toggles to move from overtravelled to undertravelled position, with resultant collapse of all the toggles and movement of the contact members 4 to open circuit position.

In subsequently reclosing the circuit breaker mechanism by rotation of the handle 61 in counter-clockwise direction as viewed in Fig. 2, the actuator 58 by its upper lug 59 depresses the operating lever 36, which then presses upon the outer end of the cam 35, which in turn by another portion thereof engages the pin 54 and rotates the lever 51, in opposition to spring 52, to position bringing the armature 50 close to the poles 49 of the low voltage magnet, which, if there is voltage of sufficient magnitude upon the circuit, will then attract and hold the armature 50 in the position indicated in Fig. 1.

What I claim is:

1. Circuit breaker mechanism comprising a movable contact member, an overtraveling toggle for moving said contact member to and restraining it in normal position, an independently movable operating member, and a latch forming a detachable connection between said operating member and said toggle.

2. Circuit breaker mechanism comprising a movable contact member, an overtraveling toggle for moving said contact member to and restraining it in normal position, an independently movable operating member, a latch forming a detachable connection between said operating member and said toggle, and electro-responsive means for moving said toggle to undertravelled position and for actuating said latch to disengage said operating member from said toggle.

3. Circuit breaker mechanism comprising a movable contact member, an overtraveling toggle for moving said contact member to and restraining it in normal position, an independently movable operating member, a latch forming a detachable connection between said operating member and said toggle, and electro-responsive means for actuating said latch to disengage said operating member from said toggle and for thereafter moving said toggle from overtravelled to undertravelled position.

4. Circuit breaker mechanism comprising a movable contact member, an overtraveling toggle for moving said contact member to and restraining it in normal position, an independently movable operating member, a latch forming a detachable connection between said operating member and said toggle, an electrically operated member for moving said toggle from overtravelled to undertravelled position, and a member

carried by said electrically operated member for actuating said latch to disengage said operating member from said toggle.

5. Circuit breaker mechanism comprising

5 a movable contact member, an overtravelling toggle for moving said contact member to and restraining it in normal position, an independently movable operating member, a latch forming a detachable connection between said operating member and said toggle, an electrically operated member for moving said toggle from overtravelled to undertravelled position, and a member pivoted upon said electrically operated member for actuating said latch to disengage said operating member from said toggle.

6. Circuit breaker mechanism comprising a movable contact member, an overtravelling toggle for moving said contact member to and restraining it in normal position, an independently movable operating member, a latch forming a detachable connection between said operating member and said toggle, an electrically operated member for moving said toggle from overtravelled to undertravelled position, a member carried by said electrically operated member, and a latch actuator actuated by said last named member for actuating said latch to disengage said operating member from said toggle.

7. Circuit breaker mechanism comprising a movable contact member, an overtravelling toggle for moving said contact member to and restraining it in normal position, an independently movable operating member, a latch forming a detachable connection between said operating member and said toggle, an electrically operated member for moving said toggle from overtravelled to undertravelled position, a member pivoted upon said electrically operated member, and a latch actuator actuated by said last named member for actuating said latch to disengage said operating member from said toggle.

8. Circuit breaker mechanism comprising a plurality of movable contact members, an overtravelling toggle for each of said contact members for moving it to and restraining it in normal position, an operating member common to said toggles, a latch forming a detachable connection between said operating member and said toggles, a plurality of electrically operated members operative independently of each other to move said toggles from overtravelled to undertravelled position, and a tripping member carried by said electrically operated members for actuating said latch.

9. Circuit breaker mechanism comprising a plurality of movable contact members, an overtravelling toggle for each of said contact members for moving it to and restrain-

ing it in normal position, an operating member common to said toggles, a latch forming a detachable connection between said operating member and said toggles, a plurality of electrically operated members operative independently of each other to move said toggles from overtravelled to undertravelled position, and a tripping member carried by said electrically operated members for actuating said latch in advance of movement of said toggles to undertravelled position.

10. Circuit breaker mechanism comprising a plurality of movable contact members, an overtravelling toggle for each of said contact members for moving it to and restraining it in normal position, an operating member common to said toggles, a latch forming a detachable connection between said operating member and said toggles, a plurality of electrically operated members operative independently of each other to move said toggles from overtravelled to undertravelled position, and a tripping member pivoted upon said electrically operated members and moved by either of said electrically operated members with pivotal movement upon the other for actuating said latch to disengage said operating member from said toggles.

11. Circuit breaker mechanism comprising a plurality of movable contact members, an overtravelling toggle for each of said contact members for moving it to and restraining it in normal position, an operating member common to said toggles, a latch forming a detachable connection between said operating member and said toggles, a plurality of electrically operated members operative independently of each other to move said toggles from overtravelled to undertravelled position, and a tripping member pivoted upon said electrically operated members for actuating said latch.

12. Circuit breaker mechanism comprising a plurality of movable contact members, an overtravelling toggle for each of said contact members for moving it to and restraining it in normal position, an operating member common to said toggles, a latch forming a detachable connection between said operating member and said toggles, a plurality of electrically operated members operative independently of each other to move said toggles from overtravelled to undertravelled position, a tripping member carried by said electrically operated members for actuating said latch, and a latch actuator actuated by said tripping member for actuating said latch to disconnect said operating member from said toggles.

13. Circuit breaker mechanism comprising a movable contact member, an overtravelling toggle for moving said contact member to and restraining it in normal position,

an independently movable operating member, a latch forming a detachable connection between said operating member and said toggle, a low voltage magnet having a normally attracted armature, means for moving said armature to unattracted position, and means whereby said last named means actuate said operating member to disengage said latch and thereafter to move said toggle from 10 overtravelled to undertravelled position.

14. Circuit breaker mechanism comprising a movable contact member, an overtravelling toggle for moving said contact member to and restraining it in normal position, an independently movable operating member, a latch forming a detachable connection between said operating member and said toggle, a low voltage magnet having a normally attracted armature, means for moving said armature to unattracted position, and a member actuated by said means and actuating said operating member to move said toggle from overtravelled to undertravelled position.

15. Circuit breaker mechanism comprising a movable contact member, an overtravelling toggle for moving said contact member to and restraining it in normal position, an independently movable operating member, a latch forming a detachable connection between said operating member and said toggle, a housing enclosing the aforesaid mechanism, an actuator carried by said housing within the same in detached relation to said operating member, and means external to said housing for actuating said actuator for actuating said operating member in one direction for causing said latch to connect said operating member with said toggle, and in 40 opposite direction for moving said operating member in opposite direction to expand said toggle and move it to overtravelled position.

16. Circuit breaker mechanism comprising a plurality of movable contact members, an overtravelling toggle for each of said contact members for moving it to and restraining it in normal position, an operating member common to said toggles, a latch forming 50 a detachable connection between said operating member and said toggles, a plurality of electrically operated members operative independently of each other to move said toggles from overtravelled to undertravelled position, a tripping member carried by said electrically operated members for actuating said latch, a housing enclosing the aforesaid mechanism, an actuator carried by and disposed within said housing in detached relation to said operating member, and means external to said housing for moving said actuator in opposite directions for causing said latch to connect said operating member with said toggles and for moving said oper-

ating member to expand said toggles and 65 carry them to overtravelled position.

17. Circuit breaker mechanism comprising a movable contact member, an overtravelling toggle for moving said contact member to and restraining it in normal position, an independently movable operating member, a latch forming a detachable connection between said operating member and said toggle, a low voltage magnet having a normally 70 attracted armature, means for moving said armature to unattracted position, a member actuated by said means and actuating said operating member to move said toggle from overtravelled to undertravelled position, a 75 housing enclosing the aforesaid mechanism, an actuator carried by said housing within the same in detached relation to said operating member, and means external to said housing for moving said actuator to engage and move said operating member to move 80 said armature toward attracted position.

18. Circuit breaker mechanism comprising a movable contact member, means for restraining it in normal position, an independently movable operating member, a latch forming a detachable connection between said operating member and said movable contact member, an electrically operated member for actuating said restraining means 90 to free said contact member, and a member carried by said electrically operated member for actuating said latch to disengage said operating member from said movable contact member.

19. Circuit breaker mechanism comprising a movable contact member, means for restraining it in normal position, an independently movable operating member, a latch forming a detachable connection between said operating member and said movable contact member, an electrically operated member for actuating said restraining means to free said contact member, and a member pivoted upon said electrically operated member for actuating said latch to disengage said operating member from said movable contact member.

20. Circuit breaker mechanism comprising a movable contact member, means for restraining it in normal position, an independently movable operating member, a latch forming a detachable connection between said operating member and said movable contact member, an electrically operated member for actuating said restraining means to free said contact member, a member carried by said electrically operated member, and a latch actuator actuated by said last named member for actuating said latch to disengage said operating member from said contact member.

21. Circuit breaker mechanism comprising a plurality of movable contact members,

- means for restraining them in normal position, an operating member common to said contact members, a latch forming a detachable connection between said operating member and said contact members, a plurality of electrically operated members operating independently of each other to actuate said restraining means, and a tripping member carried by said electrically operated members for actuating said latch. 55
22. Circuit breaker mechanism comprising a plurality of movable contact members, means for restraining them in normal position, an operating member common to said contact members, a latch forming a detachable connection between said operating member and said contact members, a plurality of electrically operated members operating independently of each other to actuate said restraining means, and a tripping member pivoted upon said electrically operated members and moved by either of them with pivotal movement upon the other for actuating said latch. 60
23. Circuit breaker mechanism comprising a plurality of movable contact members, means for restraining them in normal position, an operating member common to said contact members, a latch forming a detachable connection between said operating member and said contact members, a plurality of electrically operated members operating independently of each other to actuate said restraining means, and a tripping member pivoted upon said electrically operated members for actuating said latch. 65
24. Circuit breaker mechanism comprising a plurality of movable contact members, means for restraining them in normal position, an operating member common to said contact members, a latch forming a detachable connection between said operating member and said contact members, a plurality of electrically operated members operating independently of each other to actuate said restraining means, a tripping member carried by said electrically operated members, and a latch actuator actuated by said tripping member for actuating said latch. 70
25. Circuit breaker mechanism comprising a movable contact member, means for restraining it in normal position, an independently movable operating member, a latch forming a disengageable connection between said operating member and said contact member, electro-magnetic means for actuating said latch, and electro-magnetic means for actuating said operating member. 75
26. The combination with a plurality of movable contact members, of means for causing their movement in unison with each other, means for restraining said contact members in normal position, an independently movable operating member, a latch forming a detachable connection between said operating member and said movable contact members, electro-magnetic means for actuating said latch, and electro-magnetic means for actuating said operating member. 80
27. The combination with a plurality of movable contact members, of means for causing their movement in unison with each other, means for restraining said contact members in normal position, an independently movable operating member, a latch carried by said operating member and forming a detachable connection between it and said contact members, electro-magnetic means for actuating said latch, and electro-magnetic means for actuating said operating member. 85
28. Circuit breaker mechanism comprising a movable contact member, means for restraining it in normal position, an independently movable operating member, a latch forming a disengageable connection between said operating member and said contact member, electro-magnetic means for actuating said latch, and electro-magnetic means for actuating said operating member. 90
29. Circuit breaker mechanism comprising a movable contact member, means for restraining it in normal position, an independently movable operating member, a latch carried by said operating member and forming a detachable connection between it and said contact member, electro-magnetic means for actuating said latch and electro-magnetic means for actuating said operating member to free said contact member from said latch and for actuating said restraining means. 95
- In testimony whereof I have hereunto affixed my signature this 15th day of February, 1923. 100
- 105

JAMES H. WYATT.
